Primary Examiner — Andrew T Nemeth(57) **CLAIM**

The ornamental design for a toy for an animal, as shown and described.

DESCRIPTION

FIG. 1 is a perspective view of a toy for an animal showing my new design;

FIG. 2 is a front view of the toy for an animal;

FIG. 3 is a rear view of the toy for an animal;

FIG. 4 is a right side view of the toy for an animal;

FIG. 5 is a left side view of the toy for an animal;

FIG. 6 is a top view of the toy for an animal;

FIG. 7 is a bottom view of the toy for an animal; and,

FIG. 8 is another perspective view of the toy for an animal. The broken lines throughout the drawing figures depict portions of the toy for animal that form no part of the claimed design.
